(57) **CLAIM**

The ornamental design for a pellet, as shown and described.

DESCRIPTION

FIG. 1 is a perspective view of a pellet showing my new design;

FIG. 2 is a front elevation view of the pellet, the right, rear, and left elevation views of the pellet being identical; and, FIG. 3 is a top elevation view of the pellet.

The broken lines in the figures are for the purpose of illustrating environmental structure only and form no part of the claimed design.
